UNITED STATES PATENT OFFICE.

VICTOR L. CROSS, OF PLATTSBURG, NEW YORK.

SPEED-INDICATOR.

1,035,085.

Specification of Letters Patent. Patented Aug. 6, 1912.

Application filed May 23, 1910. Serial No. 562,931.

To all whom it may concern:

Be it known that I, VICTOR L. CROSS, a citizen of the United States, residing at Plattsburg, in the county of Clinton and State of New York, have invented a certain new and useful Speed-Indicator, of which the following is a specification.

My invention relates to a new and useful improvement in speed and time indicators for automobiles, and the like, and has for its object to provide a simple and effective device of this description which will indicate and record the speed at which an automobile or other vehicle is traveling in such manner that the driver may readily observe the speed at any time and also have a record of the speed made at any hour, and may also observe the time.

With these ends in view my invention consists in the details of construction and combination of elements hereinafter set forth and then specifically designated by the claims.

In order that those skilled in the art to which this invention appertains may fully understand how to make and use the same, I will describe its construction in detail referring by letter to the accompanying drawing, forming a part of this specification, in which—

Figure 1, is a front view of my improved device, the cap of the governor case is removed and certain parts sectioned to clearly show the construction. Fig. 2, a sectional elevation of the device looking at right angles to Fig. 1.

In carrying out my invention as here embodied A represents the governor case, having the lugs B through which are formed holes for the passage of screws or bolts for securing it to a dash board or other suitable surface, and C is the cap or cover adapted to be secured to the case, for inclosing the mechanism of the governor.

D is a hollow spindle fitted to slide vertically in the bearing E and having formed therewith the stem F, which passes through the stuffing box G threaded into the case and cap.

H is a shaft the upper end of which is fitted to revolve in the hollow spindle D while its lower portion is journaled in the bearing I. The lower end of this shaft is reduced in diameter and passes through the stuffing box J, having attached thereto the flexible shaft K, and this flexible shaft is

intended to be driven from one of the wheels of the vehicle in the usual manner. On the shaft H is secured the collar L, while the collar M is fitted to slide on said shaft and to these collars are pivoted the arms N of the ball governor, a spring O being interposed between the collars for normally forcing the collar M upward to draw the balls P toward each other. The spindle D has a flange R formed on its lower end over which fits a cap Q, and this cap is secured to the collar M or an extension thereof, so that the revolving of the collar with its shaft will not revolve the spindle, but will cause said spindle to rise and fall with the vertical movements of the said collar as will be readily understood.

S represents the casing of the indicator which may be of any design for inclosing an ordinary clock mechanism 2, and the hour shaft T of said mechanism is adapted to revolve the dial V, having marked thereon twenty-four main divisions representing the twenty-four hours of the day, and subdivisions representing quarter and half hours.

V is an indicating hand or pointer secured to the casing so as to register with the time divisions and thereby indicate the time. Concentric circles may be marked on the dial or a separate disk having such lines attached to said dial, said circles being designated by figures indicating miles per hour.

W is an arm secured to the short shaft X and carrying a pencil point Y, and Z is a lever also secured to the short shaft, its outer end being connected to the stem F.

From the foregoing description the operation of my improved speed indicator will be as follows: The governor shaft H being revolved at a speed relative to the speed of travel of the vehicle, the balls will move outward in proportion to said speed thus drawing down the collar and consequently the spindle against the action of the spring O. This action will draw the lever Z downward and thereby swing the arm W outward, carrying the pencil point more or less from the center of the disk, and by reference to the circles with which the point registers at any particular time the speed of the machine will be known, and if the pencil point is arranged to trace a line on the disk as the latter is revolved by the clock mechanism a record will be had of the speed of the machine at any particular time or for the whole time of the twenty-four hours. Oil

may be supplied to the interior of the governor case for lubricating the parts contained therein.

Having thus fully described my invention 5 what I claim as new and useful is:—

1. In a speed indicator, a casing having a dial fitted to revolve therein, said dial having divisions of time and concentric circles marked thereon, means such as the hour 10 shaft of a clock for revolving said dial, a stationary hand for registering with said divisions as the dial revolves, an arm adapted to swing across the face of the dial, marking means carried by said arm, a short shaft 15 to which the arm is secured, a lever also attached to said shaft, a stem pivoted to the outer end of the lever, a hollow spindle with which the stem is formed, a bearing in which said spindle is adapted to slide, a 20 governor shaft fitted to revolve in the spindle, a flexible shaft for revolving the governor shaft, and means carried by the governor shaft for raising and lowering the spindle relative to the speed of said shaft, as 25 specified.

2. In a speed indicator, a casing having a dial fitted to revolve therein, said dial having divisions of time and concentric circles marked thereon, means such as the hour 30 shaft of a clock for revolving said dial, a stationary hand for registering with said divisions as the dial revolves, an arm adapted to swing across the face of the dial, marking means carried by said arm, a short shaft to 35 which the arm is secured, a lever also attached to said shaft, a stem pivoted to the outer end of the lever, a hollow spindle with which the stem is formed, a bearing in which said spindle is adapted to slide, a 40 governor shaft fitted to revolve in the spindle, a flexible shaft for revolving the governor shaft, a bearing in which the lower portion of the shaft revolves, a collar secured to the shaft, another collar slidably mounted 45 on said shaft, a spring interposed between

said collars, governor arms pivoted to the collars, balls carried by said arms, and a case inclosing the operating parts of the governor, said case adapted to hold a supply of oil.

3. In a speed indicator, a suitable casing, a clock mechanism mounted in said casing, a dial having divisions of time and concentric circles marked thereon, revolved by said clock mechanism, an arm adapted to swing across said dial, marking means carried by said arm, a short shaft carrying said arm, a lever carried by said short shaft, a stem pivoted to the free end of the lever, a hollow spindle formed with said stem, a governor 60 shaft adapted to be revolved through a suitable connection with the vehicle wheel, said governor shaft fitted to revolve in the hollow spindle, and means carried by the governor shaft for moving the spindle along 65 the governor shaft according to the speed of the vehicle, thereby causing the arm to move across the dial as specified.

4. In a speed indicator, the combination 70 of a casing and revolving time dial; a pivoted arm carrying marking means adapted to move across the dial, a lever connected with said arm, a governor shaft, means for revolving said governor shaft, a governor mounted on said governor shaft, comprising 75 two collars, and suitable connecting means, resilient means for normally forcing said collars apart and means for connecting the lever directly to the governor, comprising a stem pivoted to the outer end of the lever, 80 and a hollow integral spindle surrounding the governor shaft and connected to one of the collars of the governor.

In testimony whereof, I have hereunto affixed my signature in the presence of the 85 two subscribing witnesses.

VICTOR L. CROSS.
